[57]

CLAIM

The ornamental design for a combined perfume bottle and stopper, as shown and described.

DESCRIPTION

FIG. 1 is a perspective view of the combined perfume bottle and stopper showing the new design;

FIG. 2 is a front view thereof, the rear and side views are the same;

FIG. 3 is a top view thereof;

FIG. 4 is a bottom view thereof; and,

FIG. 5 is a bottom view of a second embodiment.

The portions of the second embodiment that are not shown in the drawings are the same in appearance as the first embodiment.
